J. S. JUDELL

DRAIN FIXTURE

Filed Feb. 16, 1925

UNITED STATES PATENT OFFICE.

JULIUS S. JUDELL, OF MILWAUKEE, WISCONSIN.

DRAIN FIXTURE.

Application filed February 16, 1925. Serial No. 9,578.

This invention relates to drain fixtures for tubs, basins, sinks and the like.

Considerable difficulty has been experienced in designing fixtures which will permit

5 concealment of the drain valve operating mechanism and yet render the operating parts readily accessible for cleaning and repair. This difficulty is particularly pronounced in the case of built-in bath tubs in 10 which the drain and overflow pipes are wholly enclosed by the wall of the tub.

One object of the present invention is the provision of a drain fixture in which the drain valve is readily accessible and operated 15 by concealed mechanism.

Another object is to simplify and otherwise improve the construction and operation of devices of this character.

Other objects and advantages will appear 20 from the following description of an illustrative embodiment of the present invention.

The single figure of the drawing is a sectional view of a combined drain and overflow fixture constructed in accordance with 25 the present invention.

The fixture selected for illustration comprises an overflow pipe 10 and drain pipe 11 both communicating with a discharge or soil pipe 12 through the usual T-fitting 13. An 30 elbow 14 is fixed to the upper end of the pipe 10 and adapted to register with the usual overflow opening 15 formed through the end wall 16 of the tub. This elbow is flanged, as at 17, or otherwise fashioned, to bear upon 35 the outer face of the tub. An escutcheon 18, similarly fashioned, bears upon the inner face of the tub and is provided with the usual openings 19 through which water may flow from the tub to and through the elbow 40 14 and pipe 10. The wall of the tub is clamped between the elbow 14 and escutcheon by any appropriate means, such as a pair 45 of screws, one of which is shown at 20, which extend through the escutcheon and are threaded into appropriate lugs 21 carried by the elbow.

An elbow 22 fixed to the end of pipe 11 is adapted to register with the usual drain opening 23 formed through the bottom 24 of 50 the tub. The open end of this elbow is flanged, as at 25, or otherwise fashioned, to bear against the outer face of the bottom of the tub, and is internally threaded to receive the threaded extension 26 of a hollow valve seat 27. The valve seat is provided with a flange 28, adapted to bear upon

the inner face of the bottom of the tub, so that the bottom wall of the tub may be securely clamped between the valve seat 27 and elbow 22.

60 The port or passage 29 through the valve seat is controlled by a valve 30 in the form of a disk having a depending peripheral flange 31 adapted to project into a corresponding groove 32 formed in the exposed 65 face of the valve seat and surrounding the passage 29. The valve carries a rigid stem 33 depending through the passage 29 into the elbow 22. A valve operating chain 34 is connected to the free end of the stem 33, 70 and extends through drain pipe 11, fitting 13 and overflow pipe to an appropriate control mechanism preferably mounted in the escutcheon 18. In this instance, the control mechanism comprises a hollow rod or tube 75 35 closely fitted for lengthwise movement in an appropriate boss 36 formed as an integral part of the escutcheon. An appropriate packing gland 37 surrounding the rod 35 offers sufficient frictional resistance to 80 lengthwise movement of the rod as to yieldably retain it in any position of adjustment. The rod 35 projects through the overflow opening 15 in the tub with the inner open 85 end thereof in position to receive the chain 34. At its outer end the rod carries a hollow knob 38 constituting a suitable operating handle.

In assembling the valve and control mechanism the chain 34 is ordinarily 90 threaded through the passage 29, pipes 11 and 10, overflow opening 15, and tube 35, and the valve 30 is placed in the full line position shown before the escutcheon is placed over the overflow opening. The 95 escutcheon is then mounted in position and the tube 35 adjusted to the full line position shown. The chain 34 is then drawn upwardly through the rod 35 until all excess slack is taken up, and fixed in such position 100 within the rod by an appropriate screw 39 in the knob 38. The excess length 34' of chain extending beyond the knob 38 is then 105 cut off. This construction and method of assembly permits a ready adjustment of the valve control mechanism to fixtures of various sizes.

With the tube or rod 35 in the full line position shown, the chain 34 is slack and the valve 30 rests by gravity upon the upstanding rim 39 formed between the groove 32 and passage 29 in the valve seat 27. The 110

drain passage 29 is thus effectively closed. To open this passage it is only necessary to pull the rod 35 upwardly into the dotted line position shown. This movement of the rod is transmitted through chain 34 to the end of the valve stem 33, causing the valve 30 to tilt upwardly away from the rim 39 into the dotted line position. Water from the tub is thus permitted to escape beneath the valve and through the passage 29 and drain pipe 11. It will be noted that in all positions of the valve, a portion at least of the flange 31 remains in engagement with the groove 32, thus providing an appropriate fulcrum during this tilting or rocking action of the valve. The flange 31 and groove 32 also serve to guide the valve into proper closing position when the slack in the chain 34 is again released by shifting the rod 35 into the full line position shown.

I have discovered that the use of a tilting valve above the drain opening of the tub results in an increased flow therethrough. This increased flow is attributed to the fact that the upwardly inclined open position of the valve tends to destroy the vortex effect which ordinarily occurs in draining a tub or basin.

Various changes may be made in the embodiment of the invention hereinabove specifically described, without departing from or sacrificing any of the advantages of the invention as defined in the appended claims.

35 I claim:

1. In a drain fixture the combination of an overflow passage, a drain passage in open communication therewith, a valve normally covering said drain passage, an element depending from beneath said valve into said drain passage, and a flexible tension transmitting means in said overflow passage connected with said element for pulling the same laterally to thereby lift said valve.

45 2. In a drain fixture the combination of

an overflow pipe, a drain passage, a valve cooperating therewith and movable axially thereof, a centrally disposed member depending from said valve and extending within said passage, and tension transmitting means associated with said member and operable to tilt said valve.

50 3. In a drain fixture the combination of a valve seat having a drain passage therethrough, a valve resting on said seat to close said passage and so arranged as to be movable axially thereof, said valve having a downwardly projecting stem, and flexible tension transmitting means secured to said stem and operable to tilt said valve to effect 55 adjustment thereof.

4. In a drain fixture the combination of a valve seat having a drain passage therethrough and a groove encircling said passage, a disk valve resting on said seat to close 60 said passage and having a flange engaged in said groove, a member depending from said valve and means pulling laterally on said member for tilting said valve to open said passage.

65 5. In a drain fixture the combination of a valve seat having a drain passage therethrough, a valve resting on said seat to close said passage, interengaging means between said valve and seat to restrain said valve against lateral movement on said seat, a member depending from said valve and means pulling laterally on said member for 70 tilting said valve to open said passage.

75 6. In a drain fixture the combination of an overflow passage, an escutcheon associated therewith, a drain outlet and cooperating valve, a hollow rod adjustably carried by said escutcheon and projecting into said passage, and flexible means anchored at one 80 end within said rod and connected with said valve for adjusting said valve.

85 In witness whereof, I hereunto subscribe my name this 2nd day of February, 1925.

JULIUS S. JUDELL.
